UNITED STATES PATENT OFFICE.

FRANS O. JOHNSON, OF SEATTLE, WASHINGTON, ASSIGNOR OF ONE-THIRD TO ALBERT J. ALLEN, OF SEATTLE, WASHINGTON.

JOINTING TOOL.

Application filed June 27, 1921. Serial No. 430,672.

To all whom it may concern:

Be it known that I, FRANS O. JOHNSON, a citizen of the United States, residing at Seattle, in the county of King and State of Washington, have invented a new and useful Improvement in Jointing Tools, of which the following is a specification.

The object of my invention is the provision of a tool especially adapted for use in brick masonry wherein it is desired to make grooved joints in the mortar between bricks as laid, either to give the work a more pleasing appearance, or for the reception of mortar used in a joining finish.

To this end, I provide a tool made of a single strip of sheet metal so cut and bent as to embody a bricklayer's implement, light in weight and handy to use; one that will cut away the soft rough mortar between laid bricks and make a suitable, evenly gauged recess therein for the purposes mentioned. The tool is simple in construction, effective in operation, and can be produced at a lower cost, so far as known to me, than any other device in its class.

In the accompanying drawings—

Figure 1 is a view, in perspective, showing the tool in operative position, and in connection with bricks and mortar joints.

Fig. 2 is a front view of the device complete.

Fig. 3 is a side view of the tool, including brickwork and a mortar joint, illustrating the operation of the device in cutting and gauging a groove.

Referring more particularly to the drawings, A designates the tool complete, formed from one piece of metal, and made preferably of sheet steel. B denotes its flat body portion, and C a tongue cut out of the body and offset, as better shown in Fig. 3. This tongue is provided with a cutting edge D, and functions as a chisel or plow in cutting out the desired groove in the mortar between bricks.

One end of the body is kerfed into two portions, one of which remains in the plane of the body and is equipped with a cutting edge E, the other is bent at right angles to the plane of the body and extends in a direction opposite to that of the tongue, is provided with a cutting edge, and designated as F. These two portions are designed for cutting out mortar in places not easily accessible to said tongue.

The other end of the body is provided with an offset finger G, having a smooth upper periphery, which, for the greater portion of its length, is of a width approximately the same as the tongue, and as indicated at H. It terminates in a cutting edge, denoted by I. This finger is utilized as a handle and also as an instrument for smoothing out a groove while the mortar is in a plastic condition. J is used to designate brickwork, K, the face of a rough mortar joint while in a soft state, and L the face of a smooth mortar joint.

In using the device it is placed as illustrated in Fig. 1; the body flush with the brickwork and the tongue extending into said rough mortar joint. As is obvious, the manual operation of the tool along the course of the joint, and the proper application of force, will cause the tongue C, with its cutting edge D, to cut out the rough joint, permit the surplus mortar to escape through the front of the body by the opening between the tongue and the body, and leave a groove of a uniform width and depth throughout the course of the joint. When the groove is thus made, the tool can be reversed and the narrow upper portion H of the offset finger placed in the groove and run along the mortar, thereby imparting a smooth finish to the groove.

The cutting edges E, F and I, add to the effectiveness of the device, in that with them, any corners or points not reached conveniently by the cutting tongue, can be readily smoothed and finished up.

The tool, constructed as it is of a single strip of sheet metal, is inexpensive to produce. It is of light weight and a simple implement of the masons' trade; easy to use, and having no parts which can work loose or give trouble in adjustment. As is evident, the cutting tongue can be offset by bending to give any required depth to a groove, and all the cutting edges are so located as to render them easily sharpened, when desired.

Having thus described my invention, I claim:

1. A device of the class described, comprising a flat body member, having at one end a curved handle provided with a smooth upper surface and a cutting end, the other end of the body having a section separated in two portions by a kerf, one portion de-

2
fining a cutter extending in a plane approximately parallel with the base of the handle, the other portion extending in the plane of the body and terminating in a cutting edge, an integral scraping and gauging member, of a width less than the body and not exceeding the width of the upper surface of the handle, offset from the body in a direction oppositely to said first portion, and terminating in a cutting edge.

2. A jointing tool made of a single piece of sheet metal, having a flat body, connected therewith, an offset cutting tongue of a width less than the body, an offset finger 15 having a smooth upper surface of a width no greater than the tongue, adapted to serve as a handle and a surfacer for plastic material, and an angularly disposed cutter extending from the body in a direction oppositely to that of the tongue.

3. A device of the class described, of integral construction, having a body provided

in its medial portion with an offset tongue terminating in a cutting edge, adapted to cut out and gauge a groove in plastic material, a finger at one end of the body and terminating in a cutting edge, for surfacing said groove, and a right angular portion at the other end of the body, and terminating in a cutting edge, to engage corners.

4. A device of the class described, made of a single piece of flat stock, comprising a body having an offset tongue for forming a groove in mortar joints and gauging the depth thereof, an opening between the tongue and the body through which detached mortar can be expelled from said tongue, cutting means for engaging and finishing corners in said material, and a handle having a surface adapted to smooth the face of said groove.

FRANS O. JOHNSON.
